Juan Ortega González Inventor:
By *Juan Ortega González*
Attorney.

UNITED STATES PATENT OFFICE.

JUAN ORTEGA GONZÁLEZ, OF MEXICO, MEXICO.

ELECTRIC OVEN.

1,404,361.

Specification of Letters Patent. Patented Jan. 24, 1922.

Application filed August 16, 1920. Serial No. 403,809.

To all whom it may concern:

Be it known that I, JUAN ORTEGA GONZÁLEZ, citizen of the United Mexican States, residing at Mexico city, Federal District, Mexico, have invented certain new and useful Improvements in Electric Ovens, of which the following is a specification.

This invention refers to an electric oven, the principal object being to provide an improved oven in which the heat radiation from the oven is eliminated, such oven having an outside wooden box, and also having between the oven itself and the wooden box a heat insulation formed by air, asbestos, mica or other insulating material of a similar character.

Another object of the invention is to so dispose the electric heating elements in the interior upper and lower portion of the oven that a more directly applied action on the article to be baked is obtained.

Still another object of the invention consists in providing the oven with a small window as a means of admitting light to the inside of the oven, so as to be able to inspect from the outside the baking or drying process, without the necessity of frequently opening the oven, thus eliminating the consequent loss of heat which invariably results therefrom.

These results I obtain by means of the construction, as shown in the attached drawings in which:

Fig. 1 is a perspective view of the oven with the door open, parts being broken away to show the construction in detail;

Fig. 2 is a perspective view of one of the longitudinal heating elements which form the heating grate;

Fig. 3 is a perspective view of a bar-hole for the hooked supporting bars.

With reference to the drawing: (1) shows the skeleton framework made of wooden strips which form open frames, said framework being lined on the inside five sides with metal sheets (2) and on the outside with wooden staves (3) nailed to the framework (1).

The door (4) of wood, on which is nailed a frame of wooden strips (5), covered with a metal sheet (6), has in its center an opening (7) for a lamp (8) covered with glass on the inside, and in addition a small window (9), the said opening extending through

the parts (5) and (6) as represented in Fig. 55 1. A wire (10) is connected to a button (11) to turn the light on or off, which will permit the inspection of the interior of the oven; the wire (10) being supplied with current from the main feed wire connected 60 at the back of the oven by means of a contact, not shown, which also supplies the electric current to the coiled heating wires (12). These wires (12) are held within the individual channel-irons (13), which 65 constitute the electric heating grate, each one of the triangular channel-irons (13) being lined with asbestos or mica (14) on the inside, and passing through the sheet metal sides (2) of the oven, from which they are 70 insulated by means of the bushings (15) piercing the walls (2).

The radiator resistance wires (12) pass through the bushings (15) and connect with the wires (16) on the outside of the metallic 75 lining (2) of the oven.

In the example shown the oven has four lower and four upper heating rods or channel-irons (13), and about midway in the interior of the oven the supporting bars (17) 80 are mounted in flared perforations (18) formed in the side walls of the oven on which bars the moulds or pans are placed. It will be seen that the heat will radiate from the heating rods in a well distributed manner, 85 from the bottom up as well as from top to bottom, and that each time it is necessary to inspect the contents of the oven, all that has to be done is to turn on the light (8) and look through the small window (9), 90 without the necessity of opening the door except when the baking is finished.

Having thus described my invention what I claim is:

1. An electric oven, comprising a non-metallic outer framework, an inner lining of sheet metal, and an intermediate non-metallic skeleton framework to opposite sides of which the outer framework and the lining are secured, said intermediate framework 100 providing spaces for the reception of a heat-insulating medium; in combination with heating elements disposed within the oven, and means for supplying electric current thereto.

2. An electric oven according to claim 1, in which both the outer framework and the intermediate framework are constructed of

wood, the second-named framework consisting of wooden strips joined together to form open frames.

3. An electric oven, provided with a plurality of interior heating units arranged to form a grate, each such unit comprising a channel iron lined with heat-insulating material and containing a resistance element

projecting at opposite ends beyond the ends of the channel iron; and current supply means connected with the ends of said resistance elements.

In testimony whereof I have affixed my signature.

JUAN ORTEGA GONZÁLEZ.
